UNITED STATES PATENT OFFICE.

AUGUSTE CAMILLE EDMOND RATEAU AND GASTON SAUTTER, OF
PARIS, FRANCE.

STEAM-TURBINE.

SPECIFICATION forming part of Letters Patent No. 782,623, dated February 14, 1905.

Application filed December 9, 1903. Serial No. 184,507.

To all whom it may concern:

Be it known that we, AUGUSTE CAMILLE EDMOND RATEAU and GASTON SAUTTER, residing at Paris, France, have invented a new and useful Improvement in Steam-Turbines, which improvement is fully set forth in the following specification.

The present invention has for its object a turbine formed of two drums mounted upon a common shaft for the purpose of employing either simultaneously or successively low-pressure steam derived from a primary engine of any type and high-pressure steam derived direct from the boiler, the working being so conducted that there is no appreciable loss of energy. Each of the said drums constitutes a turbine—one a high-pressure turbine, the other a low-pressure turbine. The turbines are mounted upon a common shaft, from which it results that the assemblage forms a single apparatus. The low-pressure turbine or drum receives exhaust-steam from a primary engine, which steam then passes to a condenser. The other high-pressure turbine or drum receives live steam derived from a boiler through an automatically-governed steam-inlet, the said steam being then exhausted into the low-pressure turbine. In order to allow the assemblage to work satisfactorily, the following difficulties must be overcome: First, the admission of live steam to the high-pressure turbine must be completely automatic and without the intervention of the engineer; second, the speed-governor must be able to act upon the assemblage as it acts in ordinary cases without it being possible for any racing to take place; third, and lastly, in order that the high-pressure turbine shall not be a cause of loss of energy when the low-pressure turbine is alone being driven—that is to say, when the motive force is derived from exhaust-steam from a primary engine passing to the low-pressure turbine alone—it is necessary to arrange that the high-pressure turbine shall rotate in a vacuum when not utilizing live steam. The arrangement shown in the annexed drawings fulfills the required conditions.

Figure 1 shows diagrammatically the machine as a whole. Figs. 2, 3, and 4 show a

modification of an automatically-governed inlet for the passage of steam to the high-pressure turbine. Fig. 5 is an enlarged view of a valve. Figs. 6 and 7 are enlarged details of the connection between the governor and throttle-valve. Fig. 8 is a general view showing the relation to a boiler and engine.

1 is the low-pressure turbine, which receives steam through the pipe 2 and which exhausts to the condenser through the pipe 3.

4 is the high-pressure turbine, arranged, as shown, upon the shaft 5, common also to the first turbine, the two turbine-drums having placed between them the centrifugal governor 6. The high-pressure turbine 4 receives live steam through the end 7 and exhausts through the tube 8 and the pipe 9, which pipe leads the steam to the pipe 2, leading into the low-pressure turbine 1. Situated between the exhaust-pipe 8 and the inlet-pipe 2 are, moreover, a check-valve 10 and a throttle-valve 11. The exhaust-steam derived from the primary engine passes through the pipe 12 into the chamber 13 containing the throttle-valve; but prior to the inlet into the chamber 13 there is placed a double-seated valve 14. The said valve is mounted on a spring 15, which must be overcome by the steam before it is able to pass into the turbine. The valve 14, usually free upon the spring 15, can nevertheless be kept fast upon its seat by means of the hand-wheel 16 when it is desired to stop the machine.

The throttle-valve 11 consists of a cylindrical piston which moves in the interior of the shell 17, which is provided with a circular orifice 18. The rod of the said piston is connected through the crank 19 and the connecting-rod 20 to the governor-sleeve in such a manner that the latter can open or close the circular orifice 18 through which the steam is forced to pass to arrive at the inlet-pipe 2 of the low-pressure turbine 1. The pipe 9 from the high-pressure turbine 4 leads, as does the pipe 12, into the chamber 13 containing the throttle-valve.

The check-valve 10 rests on its seat by reason of its own weight, and it is, moreover, thrust down by a spring 21. The steam is forced to

lift the valve to pass out from the high-pressure turbine. A handle 22 allows the valve 10 to be kept open when desired. This may be useful when after closing the double-seated 5 valve 14 by the hand-wheel 16 the engine is being worked by means of live steam only.

The automatic inlet for steam is seen on the left-hand portion of the drawings above the cylinder 4. It consists of a piston and a shell 10 23, exactly analogous to the main throttle-valve acted on by the governor. The rod 24 of the obturating-piston is governed in this case by a flexible rubber diaphragm 25, placed 15 in a flat circular box. The lower portion of the box is submitted to atmospheric pressure, while the upper portion is put into communication with the pipe 9 and the chamber 13 containing the throttle-valve by means of the pipe 26. The diaphragm is also submitted to 20 an upward stress or at times to a downward stress by means of a lever 27, acted upon by an adjustable spring 28. The chamber which contains the shell 23 of the obturator is placed in communication with the boiler by the pipe 25 29, and, on the other hand, the interior of the shell is placed in communication with the chamber 30, provided in the end 7 of the high-pressure turbine 4. The chamber 30 precedes the first steam-inlet to the turbine. It will 30 be seen in the arrangement of automatic inlet that the rubber diaphragm 25 falls and closes the obturator when the pressure in the pipe 9, transmitted through the pipe 26, exceeds a given limit and that, on the contrary, 35 the diaphragm rises and opens the obturator when the pressure falls below the limit.

In the lower portion of the drawings an arrangement is shown by which a vacuum is formed in the high-pressure turbine when the 40 automatic steam-inlet is closed. This arrangement comprises a piston-valve 31, placed at the end of the pipe 32, the said pipe being connected to the lower portion of the high-pressure-turbine cylinder. This piston is 45 acted upon by a spring which tends to thrust it downward, and consequently to open communication between the pipe 32 and the small chamber 33, which in its turn communicates with the condenser through the tube 34. 50 When, therefore, the high-pressure turbine 4 receives no live steam, the piston 31 is forced downward and a vacuum is formed throughout the turbine 4 through the intermediary of the pipe 34 and the pipe 32; but so soon 55 as live steam passes into the turbine the pressure rises in the admission-chamber 30, which communicates through the pipe 35 with the lower end of the piston 31, and so soon as the pressure is sufficient the piston 31 again rises 60 in compressing its spring and closes the pipe 32, consequently closing communication between the high-pressure turbine and the condenser. The converse takes place when the inlet of live steam ceasing equilibrium of

pressure is established throughout the high-pressure turbine.

The system works in the following manner:

First. When the exhaust-steam from the primary engine arrives in a quantity sufficient to of itself feed the low-pressure turbine 1, the 7- pressure of the pipe 12 in the chamber 13 and in the pipe 9 is sufficient to maintain the obturator of the automatic inlet for live steam closed. No steam then passing to the high-pressure turbine, the check-valve 10 remains 75 closed, and, on the other hand, the turbine 4 is made to connect with a vacuum by means of the automatic piston 31 and does not consume energy by friction of the wheels in inert fluid. The governor 6 acts upon the throttle-valve 80 11 in the ordinary way.

Second. So soon as the low-pressure steam no longer suffices for the demands of the low-pressure turbine 1 the pressure in the chamber 13 falls, and then the automatic inlet opens, 85 allowing a certain quantity of live steam to pass into the high-pressure turbine. This quantity is self-regulated and is that which is necessary to maintain the pressure in the admission-chamber 13 constant. The working pressure 90 can be modified as desired by changing the tension of the spring 28, which acts upon the diaphragm of the automatic inlet. Moreover, as has been above explained, so soon as the automatic inlet opens the piston 31 closes 95 communication between the high-pressure turbine and the condenser. In this case the action of the governor is the same as that hereinafter described.

Third. If the supply of low-pressure steam 100 ceases completely, the live steam suffices to alone feed the two turbines; but it is then necessary to prevent the steam flowing through the pipe 12. It is mainly for this that the double-seated check-valve is provided. 105

Lastly, it will be seen that by acting upon the throttle-valve 11 the governor 6 can, moreover, govern the speed of the group of turbines. The throttle-valve on closing lessens the quantity of steam delivered to the low-pressure 110 turbine and at the same time causes the pressure in the chamber 13 to rise, (owing to the check-valve 14,) and consequently causes the automatic inlet for live steam to be partially or completely closed. Strictly speaking, when 115 the governor completely closes the valve 11 a vacuum can prevail throughout the low-pressure turbine, while, on the contrary, if the automatic inlet does not happen to work, in consequence of abnormal friction in its movements, the boiler-pressure may establish itself not only in the high-pressure turbine 4, but also in the pipe 9 and in the chamber 13 to as far as the valve 14.

In order to guard against the evils which 125 abnormal friction of the automatic inlet might give rise to, a small piston-distributer acted upon by the governor may be arranged in con-

action with the pipe 26, which places the pipe 26 into communication either with the condenser when the governor arrives at the end of its movement for opening or with the boiler when the governor arrives at the end of its movement for closing. In this manner the automatic inlet is placed to a certain degree under the control of the governor itself, and for the small forces corresponding to the variations of pressure in the pipe 9 there is substituted the great forces due to the difference of pressure between the boiler and the condenser.

In place of the automatic inlet shown in Fig. 1 the arrangement hereinafter described, and shown in Figs. 2, 3, and 4, may be used. The latter figure is a section, to a larger scale, on the line *ab* of Fig. 2. The obturator instead of being on the steam-inlet pipe situated in front of the cylinder of the high-pressure turbine is arranged on the cylinder *end* itself, at the inlet to the first distributor, in such a manner that the obturator closes more or less the channels of the first distributor. The advantage is that the total expansion of the steam is then in all cases utilized, while with the arrangement described above and shown in Fig. 1 when the automatic inlet is partially open a certain portion of the energy of the steam is lost by expansion at the orifice uncovered by the obturator. Figs. 2, 3, and 4 show the details of the obturator and the method of governing it automatically. Steam passes through the pipe 36 into the circular chamber 37, in which the circular obturator 38 is arranged. The obturator is cylindrical at its periphery and moves with little friction in the interior of a cylinder. In the wall of said cylinder at certain spots and symmetrically arranged over its surface there open out the channels of the primary distributor 39, which lead steam into the paddle 40 of the first moving wheel. Fig. 3 shows at 41 openings formed in the obturator 38 opposite the partitions 42 of the distributor. It will be seen that by turning the obturator more or less one, two, three, or more channels in each group of the distributor 39 will be closed by the edge of the openings. The obturating-valve is moved by means of a toothed sector 43, Fig. 3, and of a pinion 44, mounted at the end of a rod 45, Fig. 2, which may be moved by hand by means of an outside wheel 46 or automatically by means of the pinion 47 and rack 48, Fig. 4. The rack 48 is in one piece with the pistons 49 and 50, which are of different diameter and which move in cylinders 51 and 52. The cylinder 51 is put into communication through the pipe 53 with the chamber 13; Fig. 1, which contains the low-pressure-turbine throttle-valve, and the cylinder 52 is placed into communication through the pipe 54 either with the outside atmosphere or with the pipe supplying boiler-steam. On the other hand, the space 55 comprised between the two pistons is put into communica-

cation through the pipe 56 with the condenser in such a manner as to lower the pressure in the chamber 55 as much as possible. 57 is a grease-box for lubricating the pinion 47 and the rack 48. Owing to the arrangement of the differential pistons 49 and 50, it will be seen that a constant relation is automatically established between the pressure acting upon the piston 49—that is to say, the pressure of the steam before its inlet into the low-pressure turbine—and atmospheric pressure acting upon the piston 50, or it may be the pressure in the boiler, according as the cylinder 52 is put into communication with the outside atmosphere or with the boiler. When the pressure of the steam admitted to the low-pressure turbine rises above the figure corresponding to this relation, the piston 49 moves to the left, moving with it the rack and closing the throttle-valve 38. The converse takes place if the pressure falls. It may be remarked that this arrangement of throttle-valve upon the first distributor is applicable to a turbine of any type. It merely requires that the cylinder 51 shall be connected through the pipe 53 with the chamber 37 containing the throttle-valve, while the cylinder 52 of smaller diameter than the other shall be placed in communication through the pipe 54 with the inlet-pipe for steam derived from the boiler. Under these conditions this arrangement will close or open the throttle-valve 38 in such a manner that there is a constant relation between the pressure in the chamber 37, Fig. 2, and the boiler-pressure. The centrifugal governor acting upon a throttle-valve placed in front of the chamber 37 as the throttle-valve 11 in Fig. 1 is arranged in front of the low-pressure turbine the movements of the obturating-valve placed in the chamber 37 will follow those of the throttle-valve exactly as if it were subjected to it.

The hub 58 of the valve 14, to which is fixed the valve-rod 59, has depending from it a tubular extension 60, passing with mild friction through a guide-piece 61. On the other hand, the end 62 of the rod 59 enters freely in a recess 63 of the upper valve-seat 64, which is made of a diameter slightly larger than that of the end 62. The lower end of the rod 59 is provided with an expansion 65, incased in a tubular casing 66 in which it can slide freely, such movement being limited only when said expansion reaches either end of the casing 66. Casing 66 is supported on the upper end of a screw-threaded rod 67, provided with a hand-wheel 16, and may thus be moved vertically. On the rod 59 is arranged a spring 15, one end of which abuts either directly against the bottom of the recess in the tubular extension 60 or against a washer 68, preferably integral with the rod 59, while the other end of said spring abuts against the top of the casing 66, thus tending to press valve 14 on its seat against the pressure of the incoming steam. Should it be desired to keep valve 14 fast on

its seat—for instance, for stopping or when it is desired to work the engine by means of live steam only, the valve 10 being then preferably kept open by means of handle 22—it is only necessary to screw the rod 67 upward, so as to bring the bottom of casing 66 to bear on the end 65 of rod 59. Should the valve 14, on the other hand, have a tendency to stick to its seat after it has been relieved of the upward pressure of rod 67 for starting the engine, the upper part of the casing 66 can by unscrewing the rod 67 be brought to bear on the expansion 65 of valve-rod 59 in order to withdraw the valve from its seat by a further downward movement of rod 67 and hand-wheel 16.

In Fig. 8 reference-numerals 68 and 69 indicate, respectively, the boiler supplying direct steam to the high-pressure drum and the engine which exhausts into the passage leading to the low-pressure drum. The boiler and engine are of any ordinary type, the efficient operation of the invention not depending in any way upon the specific form of motor or motive-fluid supply.

Having now particularly described and ascertained the nature of our said invention and in what manner the same is to be performed, we declare that what we claim is—

30 1. A turbine consisting of high and low pressure drums mounted upon a common shaft, the low-pressure drum receiving the exhaust from the high-pressure drum, a throttle-valve arranged in the passage between the two drums, an inlet-valve controlling the entrance to the high-pressure drum, and means operating automatically to actuate the inlet-valve as the pressure in the passage varies from a predetermined point.

40 2. The combination, with a motor, and a source of motive fluid, of a turbine comprising two drums mounted upon a common shaft, one drum arranged to receive and to utilize the exhaust from the motor, the other drum receiving its motive fluid direct from the motive-fluid supply, an inlet-valve arranged in the passage from the source of motive fluid to the drum, and means operating automatically to open said valve when the pressure of 50 the exhaust from the motor falls below a predetermined point.

55 3. The combination, with an engine, and a boiler, of a turbine comprising high and low pressure drums mounted upon a common shaft, the low-pressure drum arranged to receive and to utilize the exhaust from the engine, the high-pressure drum receiving its motive fluid from the boiler, an inlet-valve controlling the passage from the boiler to the 60 high-pressure drum, and means operating automatically to open said valve when the pressure of the exhaust from the engine falls below a predetermined point.

4. The combination, with an engine, and a

boiler, of a turbine comprising high and low pressure drums mounted upon a common shaft, the low-pressure drum arranged to receive and to utilize the exhaust from the engine and from the high-pressure drum, the high-pressure drum receiving its motive fluid from the boiler, a check-valve controlling the exhaust from the engine, a second check-valve controlling the exhaust from the high-pressure drum, a throttle-valve arranged in the passage between the check-valves and the low-pressure drum, an inlet-valve controlling the passage from the boiler to the high-pressure drum, and means operating automatically to actuate said valve as the pressure in the passage between the two drums varies from a predetermined point.

5. The combination, with an engine, and a boiler, of a turbine comprising high and low pressure drums, mounted upon a common shaft, the low-pressure drum arranged to receive and to utilize the exhaust from the engine and from the high-pressure drum, the high-pressure drum receiving its motive fluid from the boiler, a check-valve controlling the exhaust from the engine, a second check-valve controlling the exhaust from the high-pressure drum, means for holding said check-valves closed, a throttle-valve arranged in the passage between the check-valves and the low-pressure drum and controlled by a governor, 85 an inlet-valve controlling the passage from the boiler to the high-pressure drum, a diaphragm controlling said valve, a passage leading from one side of said diaphragm to the passage between the two drums, and a communication between the other side of said diaphragm and the atmosphere, whereby any variation of pressure in the passage between the two drums will cause a movement of the diaphragm to open or close the inlet-valve. 100 105

6. A turbine comprising high and low pressure drums mounted upon a common shaft, means for supplying the low-pressure drum with motive fluid independent of the high-pressure drum, and means for connecting the high-pressure drum with a condenser. 110

7. A turbine comprising high and low pressure drums mounted upon a common shaft, means for supplying the low-pressure drum with motive fluid independent of the high-pressure drum, an inlet-valve controlling the entrance of motive fluid to the high-pressure drum, a passage leading from the exhaust side of the high-pressure drum to the condenser, a valve within said passage, a piston controlling said valve, a spring tending to normally unseat said valve, and a passage leading from the inlet side of the high-pressure drum to the pressure side of said piston, whereby when the inlet-valve to the high-pressure drum is open the pressure of the motive fluid will hold the piston up and the valve closed and when the inlet-valve is closed the valve will be un-

seated by the spring and connection made by the passage between the condenser and the high-pressure drum to cause a vacuum therein.

8. A turbine comprising high and low pressure drums mounted upon a common shaft, a passage communicating between the exhaust of the high-pressure drum and the inlet of the low-pressure drum, means for supplying motive fluid to said passage independent of the high-pressure drum, a check-valve arranged in the exhaust from the high-pressure drum, an inlet-valve controlling the passage of motive fluid to the high-pressure drum, and means operating automatically to close the inlet-valve 15 when the pressure in the passage exceeds a predetermined point and to open the inlet-valve when the pressure falls below such point, in combination with a passage leading from the high-pressure drum to a condenser, and 20 means operating automatically to open said passage when the inlet-valve is closed and to close said passage when the inlet-valve is open, whereby a comparative vacuum is formed in the high-pressure drum when the same is running idly.
9. The combination, with an engine, and a boiler, of a turbine comprising high and low pressure drums mounted upon a common shaft, the high-pressure drum receiving its 30 motive fluid from the boiler, the low-pressure drum receiving and utilizing the exhaust from
- the high-pressure drum and also from the engine through a common passage, a check-valve controlling the exhaust from the engine, a second check-valve controlling the exhaust from the high-pressure drum, means for holding the first check-valve seated, a throttle-valve controlling the inlet from the passage to the low-pressure drum, a governor controlling said throttle, an inlet-valve controlling the 35 passage of motive fluid from the boiler to the high-pressure drum, a diaphragm operatively connected with the inlet-valve, a passage leading from one side of said diaphragm to the passage between the two drums whereby a 40 variation in the pressure within said passage will affect the diaphragm and serve to actuate the inlet-valve, a passage between the high-pressure drum and a condenser, means for closing said passage when the inlet-valve is 45 open, and means for opening said passage when the inlet-valve is closed, whereby a comparative vacuum is formed within the high-pressure drum when the same is running idly.
- In testimony whereof we have signed this 55 specification in the presence of two subscribing witnesses.
